UNITED STATES PATENT OFFICE.

CHARLES W. BECK, OF NEW YORK, N. Y.

ACETYLENE-GAS GENERATOR.

SPECIFICATION forming part of Letters Patent No. 790,863, dated May 23, 1905.

Application filed June 16, 1904. Serial No. 212,832.

To all whom it may concern:

Be it known that I, CHARLES W. BECK, a citizen of the United States, residing in the borough of Manhattan, city, county, and State 5 of New York, have invented certain new and useful Improvements in Acetylene-Gas Generators, of which the following is a specification, reference being had therein to the accompanying drawings, in which—

10 Figure 1 is a vertical sectional view of the generator; Fig. 2, a similar view of the feeding mechanism, the feed-valve being in its lowermost position; Fig. 3, a detail vertical sectional view of the filter; Fig. 4, a detail vertical sectional view of the feed-valve; Fig. 15 5, a vertical sectional view of the feed mechanism, showing the valve in its uppermost position; Fig. 6, a side elevation of the means for clamping together the two sections of the 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 into which the carbid is to be poured when the members of the generator are separated and the upper part inverted for the purpose of filling the carbid-holder. The lower contracted end of the carbid-holder 6 is open to provide a feed-aperture 8, and secured to the under side of this contracted part of the holder is a housing-ring 9, which forms, in conjunction with the end of the carbid-holder 6, a receptacle to receive a flexible valve-ring 10, through which the feed-plunger is adapted to work. This ring is beveled on its upper surface to correspond with the downward and inward inclined surface of the interior of the carbid-holder. A cap 11 is threaded on the lower end of this ring and its lower end underlies and bears open the under side of the valve-ring to clamp said ring in position. To the bottom of this cap is secured a downwardly-enlarged funnel 12, the lower edge of which bears against the side wall of the standard 7 and serving when the carbid-holder is detached from the water-holder and inverted as a filling-funnel to direct the carbid through the feed-aperture. This funnel 12 is provided at its upper end with wrench-notches 13, so that it may be readily detached from the ring 9 whenever it is desired to remove the valve-ring 10.

Within the carbid-holder, at the top thereof, is secured a horizontal supporting-ring 14, whose inner portion inclines inward and downward, as at 15. In the inner end of the horizontal part of this ring is formed an annular substantially semicircular groove or channel 16. Secured to the inward and downward inclined part 15 of the supporting-ring is a downward and inward inclined filter-support 17, which is formed of foraminated sheet material and is provided with annular downward-extending ribs 18 and with a short tubular part or flange 19 at its inner lower end. Secured between the part 15 and the filter-support is a filter-cloth 20, said cloth being supported on the ribs 18, its lower end being suitably secured by a wire or other means to the tubular part 19.

The purpose of supporting the filter-cloth on the ribs 18 is to hold it away from the main portion of the support, so that gas may pass through practically the entire cloth, and, further, to prevent the perforations in the support becoming clogged with lime and dust. Rigidly secured within the plate 19 of the filter-support is the upper end of a depending central guide-tube and valve-shield 21, said shield being axially in line with the center of the feed-aperture in the valve-ring. Secured to the supporting-ring 14 is a flexible, preferably rubber, circular diaphragm 22, which, together with the horizontal portion of the supporting-ring, forms a complete gas-tight wall across the top of the carbid-holder. This diaphragm is formed near its edge on its under side with a semicylindrical annular rib or

flange 23, which fits within the correspondingly-shaped groove or channel 16, formed in the supporting-ring. Resting on the top of this diaphragm, at the edge thereof, is an annular protecting-plate 24, and on the top of this protecting-plate is secured a clamping-ring 25, this latter ring being formed with radial lugs 26, through which pass clamping-bolts secured in place by nuts 27. To the under side of the supporting-ring is secured a reinforcing cast ring 28, through which the clamping-bolts pass. From the foregoing it will be readily seen that efficient clamping means are provided for securing the diaphragm to the supporting-ring, and thereby forming the flexible gas-tight wall across the top of the carbid-holder.

To the center of the diaphragm is secured by any suitable means a depending valve-rod 29, which extends through suitable guides in the shield 21. The lower part of the valve-rod is reduced in diameter to form the shoulder 30, and the lower end of this reduced part is threaded, as at 31 in Fig. 4. Slidably mounted on this reduced part 30 of the valve-rod is a sleeve 32, which is equal in diameter to the main part of the valve-rod, and to the lower end of the sleeve is rigidly secured the lower member or stop 33 of the valve, said valve member being threaded at its lower end to receive the threaded end of the valve-rod. To lock the valve member 33 to the valve-stem, a lock-nut 34 is secured on the lower projecting end of the stem, said locking-nut being formed with a wing to enable it to be readily moved by hand without the use of a wrench or other device. The upper end of the sleeve 32 abuts squarely against the shoulder 30, formed on the valve-rod, and to this upper end is rigidly secured a small collar 35. Loosely mounted on the valve-rod and inclosing this collar is the upper valve member or stop 36. This valve member is formed of two telescopic shells 37 and 38, the diameter of the exterior shell being slightly larger than the opening in the valve-ring. These shells are fitted together very snugly, so that when in operative position they move together and form a single hollow cylindrical valve member. Within this valve member and interposed between the collar 35 and the lower wall thereof is a packing-ring, which forms a gas and water proof joint when the valve is in its lowermost position, as will be more fully described hereinafter. Secured to the lower end of the guide-tube and shield 21 is a flexible guide and closer tube 39, whose lower end is brought to a sharp edge 40, which is always in rubbing contact with the exterior of the upper stop or valve member 36. This flexible tubular guide is preferably formed of rubber and is adapted to grasp the upper valve member and to prevent gas and moist vapors passing up into the shield 21 and also serving to wipe or clean the said valve mem-

ber. The friction between this shield and the valve member is sufficient to hold the said valve member in its upper or lower position until it is forcibly moved by the valve-operating mechanism. The lower valve member is formed with an upper reduced part 33^a, which is adapted to close the opening in the valve-ring to stop the feed of carbid and to prevent the passage of gas and vapor upward from the generating-chamber, and with the lower enlarged part 33^b and an intermediate short beveled shoulder. In the normal operation of the lamp when the diaphragm 22 is raised to the limit of its movement either by gas-pressure or by the means for manually raising the valve and diaphragm, which will be hereinafter described, the beveled shoulder 33^c will register with the opening in the valve-ring and form a gas and liquid tight closure, as shown in Fig. 1.

The enlarged part 33^b is adapted to be forced into the valve-ring to form a liquid-tight joint to prevent access of water to the carbid should the lamp be overturned or sufficiently inclined during its operation. This enlarged part of the valve does not contact with the valve-ring in the ordinary operation of the lamp, the upper reduced part working therein except under abnormal conditions. By this means the wear on the valve-ring is reduced, while at the same time the liquid-tight joint is secured between the valve-ring and the valve when it is needed.

The perforated filter-support 17 and the shield 21 form a protected chamber through which the valve-rod works freely, and the filter-support also forms a chamber in which the flexible diaphragm vibrates. It will be readily understood that as the carbid-holder must be inverted when it is recharged the weight of the carbid would be brought on the diaphragm if this protected chamber were not provided. It is also clear that if this free space were not provided the carbid would rest on the diaphragm during the operation of charging and the carbid-holder become so packed that the diaphragm could not vibrate sufficiently to operate the feed-valve. The object of inclining the filter-support inward and downward is not only to secure the necessary space for the diaphragm, but also to direct any particles of dust or lime that may find their way through the filter down in the shield 21. The valve members 33 and 36, together with their connecting-sleeve 32, may be readily removed from the valve-rod after detaching the lock-nut 34, so that the shields 21 and 39 will be perfectly free, except for the cross-bars therein, permitting said dust and dirt to be readily removed therefrom. It will thus be seen that I provide means for readily cleaning from the diaphragm-chamber and the shield-tube any dust which may eventually find its way therein. The object of providing a large foraminous surface for the

filter-support is to permit the gas to flow freely into the protected chamber and to prevent as far as possible any differences in pressure between the carbid-hopper and said protected chamber. If the gas-passage into the chamber formed by the support 17 were restricted, the gas would have a tendency to force its way up along the valve-rod into said chamber and to carry with it more or less dust and lime. By giving the gas a large and practically free passage through the support 17 this tendency of the gas to pass along the valve-rod is practically eliminated.

On the upper end of the valve-rod is secured a ball-cup 41, which also acts as a clamping-nut to secure the diaphragm to the valve-rod, suitable washers being interposed between said cup and the diaphragm. The top of this ball-cup is so shaped that a stop-ball 42 will be retained therein, said ball normally resting directly over the center of the valve-rod. To retain this ball in its cup, a cap 43 is secured over said cup, said cap being provided with a central aperture in its top. To the upper side of the clamping-ring 25 is secured or formed integral therewith upward and inward extending spider-arms 44, which at their upper ends support the pressure-regulator 45. On one of these spider-arms is pivoted the operating-lever 46, which is formed with an inward-extending fork the arms 47 of which curve downward, as shown clearly in the drawings, and work under horizontal radial pins 48, secured in opposite sides of the ball-cup, as may be clearly seen in dotted lines in Fig. 10. Below its pivot this lever is formed with a short downward and outward extending cam-surface 49, said cam-surface constituting the shorter arm of the lever. Threaded through the spider-arm to which said lever is attached is an operating-screw 50, whose inner end is in such a position that it will contact with the cam-surface 49, and its outer end is provided with a milled head. To the operating-lever above its pivot and on the opposite side thereof from the cam-surface 49 is pivoted a trip-lever 51, said lever being provided with outward-extending arms 52, which embrace a portion of the operating-lever and the adjacent spider-arm 44. These arms are connected at their inner ends by the head 53, whose under surface is adapted to contact with the top of the operating-lever and whose upper surface is outwardly and downwardly inclined, as at 53^a. Loosely mounted in the adjacent spider-arm is a thrust-pin 54, whose inner end is adapted to contact with the inclined upper surface 53^a of the head 53 for a purpose which will hereinafter appear. Just below the pivot of the trip-lever the operating-lever is provided with two outward-extending stop-pins 55, with which the arms of the trip-lever are adapted to contact at certain times for a purpose which will be hereinafter described. To the outer

ends of the arms of the trip-lever are secured 5 strong coil-springs 56, the other ends of said springs being connected to the other spider-arms 44, as clearly shown in Fig. 10. In the 10 normal working position of the operating-lever and the trip-lever the line of strain brought on the trip-lever by means of the springs is above the pivot of said trip-lever, so that its head 53 is forced down against the 15 upper side of the operating-lever, said point of contact between the two levers being considerably to the left of the pivot of said operating-lever. The effect of this, of course, is that the springs 56 tend to force downward the inner forked end of the operating lever.

Secured to the bottom of the regulator-valve is a depending stop-pin 57, which is adapted to enter the ball-cup when the diaphragm 22 is raised by gas-pressure. In the normal 20 working position of the parts this depending stop-pin enters the ball-cup and contacts with the ball therein to limit the upward movement of the diaphragm and operating-lever. When the diaphragm is in this upward position, as shown in Fig. 1, the line of strain brought on the trip-lever by the springs 56 is almost in a direct line from the center of the 25 ends of the arms of said lever through the center of its pivot, so that a very slight further 30 upward movement of the operating-lever would move the trip-lever sufficiently to bring said line of strain below the pivot of said trip-lever. The result of this further upward movement of the operating-lever would be to 35 cause a stop-cam 53^b on the trip-lever to contact with a stationary stop 53^c to force the arms of the trip-lever downward and bring the line of strain below its pivot and permit the springs 56 to swing said arms downward 40 into contact with the pins 55. This will bring the strain of the springs 56 on the operating-lever below its pivot, so that it will lift the valve-rod and close the feed-valve, as shown clearly in Fig. 5. The trip-lever head 53 will 45 by the movement just described be carried upward and outward into position to be engaged by the inner end of the thrust-pin 54. This pin is of such length that when the parts are in the position shown in Fig. 5 its outer end 50 is in a position to be engaged by the under side of the operating-screw 50. By reference to Fig. 1 it will be noted that the cam-surface 53^b is formed on the trip-lever slightly to the right of its pivot, so that when it contacts 55 with the stop 53^c it will prevent further upward movement of the trip-lever, and on a further upward movement of the operating-lever the trip-lever will be turned downward slightly on its pivot, thereby carrying the line 60 of strain of the springs 56 quickly below said pivot. The object of this is to secure the throw of the trip-lever without the necessity of a considerable upward movement of the operating-lever. It will of course be understood, however, that these stops may be dis-

pensed with and the operating-lever given the necessary upward movement to secure the shifting of the trip-lever.

The operation of this part of the apparatus may be briefly described as follows: Should 70 the lamp be upset while it is in operation, the ball in the ball-cup will be displaced from its normal central position, permitting the gas to expand the gas-holder abnormally, as shown in Fig. 5. This excess movement of the lever 75 46 will throw the line of strain of the springs 56 below the pivot of the trip-lever by reason of the contact of the cam-surface 53^b with stop 53^c, thereby causing said lever to swing downward until its arms contact with the pins 55. The tension of the spring will now maintain the valve 80 closed, and the lower enlarged part of the valve member 33 will be forced into the valve-ring, as clearly shown in Fig. 5. The parts will remain in this position until the operating-screw 85 is run inward, thereby forcing inward the thrust-pin 54 and causing it to swing the trip-lever on its pivot to bring the line of strain of the springs above said pivot. As soon as this is accomplished the pull of the spring will 90 be exerted on the operating-lever above its pivot, so that as soon as said lever is free the feed-valve will be opened. By running in the screw to operate the thrust-pin the inner end of said screw has been brought into contact with the cam-surface 49 of the operating-lever, thereby locking said lever against the action of the springs and preventing the sudden and violent opening of the feed-valve. When it is desired to free the lever and permit 95 the springs to operate the valve, the operating-screw is run out. It is clear that as soon as the thrust-pin 54 is forced inward slightly the operating-lever will be moved on its pivot and the ball-cup dropped below the 100 stop-pin 57 to permit the locking-ball to return to its normal central position.

It will of course be understood that should the lamp be overturned or inclined sufficiently to reverse the operation of the spring tension 105 controlling the valve it will be desirable before again starting the generation of gas to detach the carbid-holder from the water-holder and clean the interior of the chamber 7. When the parts are detached, if it be desired the 110 valve-operating mechanism may be returned to its normal position to permit the springs 56 to move the diaphragm inward by grasping the valve and pulling it downward or into the chamber 7.

When the trip-lever is returned to its normal position by the thrust-pin 54, the cam 115 53^b will contact slightly with the stop 53^c.

To start the generator when the parts are in the position shown in Fig. 1, it is simply necessary to run out the operating-screw to permit the springs 56 to depress the feed-plunger. When the gas is exhausted from the gas-holder, the parts of the feed mechanism assume the positions shown in Fig. 2, the 120

upper stop or valve member being carried down by the collar 35 and forced into the opening through the valve-ring. This upper stop has two important functions, one of which is to close the feed-opening should a rupture occur in any part of the structure, which would permit all of the gas to escape into the atmosphere. As soon as the pressure is removed from the flexible diaphragm 5 the springs 56 would throw the valve-stem down to its lowermost position, the collar 35 carrying down with it the stop 36. The other important function of this stop is to form a dust-proof closure for the end of the guide-sleeve to prevent dust, gas, and vapor passing therein and also to close said shield during the operation of charging the carbid-holder. When it is desired to charge the carbid-holder, the valve-rod is raised to carry 10 the upper stop into the shield 21. The rod is then lowered until the collar 35 rests on the lower wall of the stop 36. This will lower the valve member 33 below the valve-ring and give the widest possible opening or passage 15 through said ring and around the shield 39 for the passage of the carbid. When the carbid-holder is charged, it is merely necessary to run in the operating-screw to lift the lower valve member 33 into the valve-ring. 20 It will be readily understood from the foregoing that the upper stop remains stationary within the shields 21 and 39 except when the gas-pressure is so reduced that the springs 56 can throw the valve to its lowermost position. This materially lessens the friction 25 of the plunger through the carbid and enables the lamp to be operated under a very low gas-pressure.

Carried by the clamping-ring 25 and extending within the carbid-holder is a gas-filter, which consists of the tube 58, connected at its upper end by a pipe 59 to a chamber 60 in the bottom of the pressure-regulator. Screwed to the lower end of this tube 58 is 30 the filter-support 61, said support being of any suitable construction, that shown consisting of two separated arms transversely fluted on their outer sides. Inclosing these arms is a filter-bag 62, the upper end of said bag being securely held to the upper end of the filter-support in such a position as to cause all the gas entering the tube 58 to pass through it. Surrounding the tube 58 and fitting within a cavity formed in the under side of the clamping-ring is a downwardly-tapered packing-ring 63. Carried by the supporting-ring 14 is a compression-sleeve 64, which surrounds the tube 58 and extends into the cavity of the clamping-ring. This sleeve is formed 35 with a downward and inward inclined inner wall which engages the packing-ring when the clamping-ring is forced down toward the supporting-ring and compresses the packing-ring to form a gas-tight joint at that point. 40 The lower end of the standard 7 is formed

with a cylindrical part 65, provided with beads 66 at its upper and lower horizontal end. At the upper end of this cylindrical part is formed an interior channel 67, which is adapted to receive a packing-ring 68, said ring being 45 provided on its outer edge with a bead to fit the interior of the upper bead 66. In the channel formed by the beads 66 is mounted a clamping or connection ring 69. This ring is formed in two sections, and these sections 50 are flexibly connected together by means of a plate 70, which is provided with an aperture 71 to receive the hook 72, formed on the overlapping end of one of the sections. This plate is adjustably connected to the other section by means of a screw 73, which passes through a slot formed in said plate, the plate and the member being provided with interlocking teeth, whereby the plate is absolutely held in its adjusted position. This adjustment is provided to compensate for the wear 55 of the packing-ring. Each of the members of the ring is provided with inward-extending cams 74, which extend through slots 74^a in the part 65 and are inwardly and downwardly beveled on their faces to adapt them to engage the correspondingly-beveled surface 5 of the flange 4. To contract this ring and cause the cams 74 to bind on the surface 5, a lever 75 is pivoted on the free end of one 60 section and is connected by a link 76 to the free end of the other section, said link being pivoted to said lever at a point between its pivot and its free end, so that when the lever is thrown downward it draws the two ends of 65 the ring toward each other. As the packing-ring 68 rests on top of the flange 4, it will be readily understood that the action of the cams 74 will be to draw said ring down tightly on 70 the top of said flange. The link 76 is formed 75 with an inward-extending flange 77, which when the lever is in its locked position engages the upper edge of said lever and limits the downward movement thereof, and the lever is provided at its free end with a finger-piece 78.

It is obvious from the foregoing description and the drawings that the working parts of the generator may be readily removed from the casing for the purpose of cleaning 80 and repair by removing the lock-nut 34 and then unscrewing the valve 33 from the valve-rod. Said valve, its attached sleeve, and the upper valve member 36 may then be removed from the valve-rod. It is also obvious that 85 by removing the four nuts 27 the clamping-ring and the attached parts may be removed, thereby giving access to all interior parts of the apparatus.

Having thus described my invention, what 90 I claim is—

1. An acetylene-gas generator comprising a carbid-holder, a water-holder, a spring-controlled feed mechanism normally tending to open the feed-valve against gas-pressure, and 95

means whereby under abnormal conditions the operation of the spring tension will be reversed and tend to close the feed-valve and maintain it closed.

- 5 2. An acetylene-gas generator comprising, a carbid-holder, a water-holder, a feed-valve, a spring normally tending to open said valve, and means operated by gas-pressure when the generator is moved a predetermined distance 10 from a vertical position to reverse the operation of the tension of the spring and thereby convert it into a valve-closing spring to maintain the valve closed.
- 15 3. An acetylene-gas generator comprising, a carbid-holder, a water-holder, a feed-valve, means operated by gas-pressure for closing said valve, means for normally limiting the movement of said valve in closing, means for opening said valve against gas-pressure, means 20 whereby when the generator is moved a predetermined distance from a vertical position the closing means will give the valve an additional movement, and means whereby this additional movement will transform the valve- 25 opening means into a valve-closing means to hold the valve closed.

4. An acetylene-gas generator comprising a carbid-holder, a water-holder, a feed-valve, a spring normally tending to depress and open 30 said valve, means operated by gas-pressure when the generator is moved a predetermined distance from a vertical position to reverse the operation of the tension of the spring and thereby lift and close the valve.
- 35 5. A feed mechanism for acetylene-gas generators comprising, a valve, means operated by gas-pressure to close said valve, means operating against gas-pressure to close the valve, and means operated by gas-pressure when the 40 generator is moved a predetermined distance from its vertical position to transform the valve-opening means into a valve-closing means to hold the valve closed.

- 45 6. A feed mechanism for acetylene-gas generators comprising, a feed-valve, means normally tending to open said valve, and means adapted to be operated by gas-pressure to transform the valve-opening means into a valve-closing means to hold the valve closed, 50 when the generator is moved a predetermined distance from the vertical position.

- 55 7. A feed mechanism for acetylene-gas generators comprising, a feed-valve, means normally tending to open said valve, and means adapted to be operated by gas-pressure when the generator is moved a predetermined distance from the vertical position to transform the valve-opening means into a valve-closing means to hold the valve closed, and means for 60 returning the valve-operating means to a valve-opening mechanism.

8. A feed mechanism for acetylene-gas generators comprising, a feed-valve, means normally tending to open said valve, means adapted to be operated by gas-pressure when the 65

generator is moved a predetermined distance from the vertical position to transform the valve-opening means into a valve-closing means to hold the valve closed, and means adapted to be operated manually to return the 70 valve-operating mechanism to a valve-opening means.

9. An acetylene-gas generator comprising, a water-holder, a carbid-holder, a movable wall or part exposed to the pressure of the gas generated, 75 a valve, means connecting said valve to the movable wall or part whereby the valve is closed by gas-pressure, means opposing the gas-pressure to open the valve, a freely-movable stop to limit the movement of the valve 80 in closing under normal conditions and adapted to move when the generator is moved a predetermined distance from the vertical position to permit the valve to have an additional movement in closing and means to transform the valve-opening means into means for holding the valve closed when the movable wall or part has been moved a predetermined distance, beyond its normal movement.

10. An acetylene-gas generator comprising, 90 a water-holder, a carbid-holder, a feed-valve, a movable wall or part, means connecting the valve to the movable wall whereby said valve will be closed by gas-pressure, a spring-actuated means for opening said valve against gas- 95 pressure, and means whereby said spring-actuated opening means will act to hold the valve closed when the wall has moved a predetermined distance.

11. An acetylene-gas generator comprising, 100 a water-holder, a carbid-holder, a movable wall or part exposed to the pressure of the gas generated, a valve, means connecting said valve to the movable wall or part whereby the valve is closed by gas-pressure, means opposing the 105 gas-pressure to open the valve, and means to transform the valve-opening means into means for holding the valve closed when the movable wall or part has been moved a predetermined distance, and means for returning the 110 valve-opening means to its normal operating condition.

12. An acetylene-gas generator comprising, a water-holder, a carbid-holder, a movable wall or part exposed to the pressure of the gas generated, 115 a valve, means connecting said valve to the movable wall or part whereby the valve is closed by gas-pressure, means opposing the gas-pressure to open the valve, means to transform the valve-opening means into means for holding the valve closed when the movable wall or part has been moved a predetermined distance, and means adapted to be manually operated to return the valve-opening means to its normal operative condition.

13. An acetylene-gas generator comprising, 125 a water-holder, a carbid-holder, a feed-valve, a movable wall subject to gas-pressure, means connecting the feed-valve to the movable wall whereby said valve will be closed by gas-pres- 130

sure, an operating-lever movable with said wall, a spring device connected to said lever and operating to open the valve, and means whereby when the movable wall has reached 5 a predetermined point the spring device will act to hold the valve closed.

14. An acetylene-gas generator comprising, a water-holder, a carbid-holder, a feed-valve, a movable wall subject to gas-pressure, means connecting the feed-valve to the movable wall whereby said valve will be closed by gas-pressure, an operating-lever movable with said wall, a spring device connected to said lever and operating to open the valve, means whereby when the movable wall is moved a predetermined distance the spring device will cause 5 the lever to hold the valve closed, and means for returning the spring device to its normal operative position.

15. An acetylene-gas generator comprising, a water-holder, a carbid-holder, a feed-valve, a movable wall subject to gas-pressure, means connecting the feed-valve to the movable wall whereby said valve will be closed by gas-pressure, an operating-lever movable with said wall, a spring device connected to said lever and operating to open the valve, means whereby when the movable wall is moved a predetermined distance the spring device will cause 5 the lever to hold the valve closed, and means adapted to be manually operated to return the spring device to its normal operative position.

16. An acetylene-gas generator comprising, a water-holder, a carbid-holder, a feed-valve, a horizontal movable wall subject to the pressure of the gas generated, means for connecting said movable wall to the feed-valve to close said valve by gas-pressure, an operating-lever operatively connected to said movable wall, a spring device connected to said lever and tending to depress the movable wall, a freely-movable body for limiting the movement of the movable wall when the generator is in an upright position and adapted to shift 5 to permit the movable wall to have an additional upward movement when the generator is out of its vertical position, and means whereby this additional travel of the movable wall will transform the valve-opening means into a valve-closing means.

17. An acetylene-gas generator comprising, a water-holder, a carbid-holder, a feed-valve, a horizontal movable wall subject to the pressure of the gas generated, means for connecting said movable wall to the feed-valve to close said valve by gas-pressure, a lever operatively connected to said movable wall, a spring device connected to said lever and tending to depress the movable wall, a freely-movable body for limiting the travel of the movable wall when the generator is in an upright position and adapted to shift to permit the movable wall to have an additional travel when the generator is out of its vertical position, and means whereby this additional travel 5

of the movable wall will transform the valve-opening into a valve-closing means, and manual means for returning the valve-opening means to its normal operative position.

18. An acetylene-gas generator comprising 70 a carbid-holder, a water-holder, a feed mechanism normally opening the feed-valve against gas-pressure, a freely-movable device to limit the movement of the valve in closing under normal conditions and shifting to permit the 75 valve to have an additional movement in closing when the generator is moved a predetermined distance from a vertical position, and means whereby this additional movement of the valve will convert the valve-opening means 80 into a valve-closing means.

19. An acetylene-gas generator comprising, a valve for closing communication between the two receptacles, means to close said valve by gas-pressure, a movable body for normally 85 limiting the movement of said valve when the generator is in an upright position and permitting said valve to have an additional movement when the generator is moved from its vertical position, means for opening said 90 valve, and means operated by the additional movement of the valve to transform the valve-opening means into a valve-closing means to hold the valve closed.

20. An acetylene-gas generator comprising, 95 a carbid-holder, a water-holder, a feed-valve, a movable wall, means connecting the valve to said movable wall, means for limiting the movement of said wall when the generator is in an upright position but permitting it to 100 have an excess movement in any other position, an operating-lever connected to said movable wall, a trip-lever carried by said operating-lever, a spring connected to said trip-lever, and means whereby the excess movement 105 of the wall will swing the trip-lever and cause the spring to pull the valve closed.

21. An acetylene-gas generator comprising, a carbid-holder, a water-holder, a feed-valve, a movable wall, means connecting the valve to 110 said movable wall, means for limiting the movement of said wall when the generator is in an upright position and permitting it to have an excess movement in any other position, an operating-lever connected to said movable wall, a trip-lever carried by said operating lever, a spring connected to said trip-lever, and means whereby the excess movement 115 of the wall will swing the trip-lever and cause the spring to pull the valve closed, and means adapted to be manually operated to return the valve-operating means to its normal condition.

22. An acetylene-gas generator comprising, a carbid-holder, a water-holder, a movable wall, a valve, means connecting the valve to 125 said movable wall, means for limiting the movement of said wall when the generator is in an upright position and permitting it to have an excess movement in any other position, an operating-lever connected to said mov- 130

able wall, a spring device connected to said lever and normally acting to open the valve, means whereby the excess movement of the wall will cause the spring device to exert an upward pull on the lever to hold the valve closed, means operating on the lever to manually close the valve and means operated by said lever-moving means to return the spring device to its normal operative position.

23. An acetylene-gas generator comprising, a carbid-holder, a water-holder, a feed-valve, a movable wall, means connecting the valve to said movable wall, means for limiting the movement of said wall when the generator is in an upright position and permitting it to have an excess movement in any other position, an operating-lever connected to said movable wall, a trip-lever carried by said operating-lever, a spring connected to said trip-lever, means whereby the excess movement of the wall will swing the trip-lever and cause the spring to pull the valve closed, an operating-screw adapted to swing the operating-lever to close the valve and means operated by said screw to swing the trip-lever on its pivot and thereby return the spring to its normal position to open the valve.

24. An acetylene-gas generator comprising, a carbid-holder, a water-holder, a feed-valve, a movable wall, means connecting the valve to said movable wall, means for limiting the movement of said wall when the generator is in an upright position and permitting it to have an excess movement in any other position, an operating-lever connected to said movable wall, a trip-lever carried by said operating-lever, a spring connected to said trip-lever, and coating stops on the trip-lever and the case whereby the excess movement of the wall will swing the trip-lever and cause the spring to pull the valve closed, an operating-screw adapted to swing the operating-lever to close the valve, and means operated by said screw to swing the trip-lever on its pivot and thereby return the spring to its normal position to open the valve.

25. An acetylene-gas generator comprising, a carbid-holder, a water-holder, a feed-valve, a movable gas-tight wall across the top of the carbid-holder, a valve-stem connected to said movable wall and carrying suitable valve devices, a ball-cup on the top of said wall, a freely movable ball therein, a limiting-stop carried by the casing and adapted to contact with the ball when the generator is in an upright position, an operating-lever connected to said movable wall, a screw adapted to engage said lever to swing it on its pivot and thereby forcibly close the valve, a trip-lever mounted on said operating-lever above its pivot, a spring connected to said trip-lever and serving in one position of said trip-lever to tend to force the feed-valve open, said trip-lever being so mounted that when the generator is moved from its upright position the

point to which the spring is attached will be swung below the pivot of the operating-lever, a stop on said operating-lever to limit the downward swing of said trip-lever and to cause said spring to exert an upward pull on the operating-lever.

26. An acetylene-gas generator comprising, a water-holder, a carbid-holder, a movable wall, a valve connected thereto and formed with an upper reduced part, means for opening said valve against gas-pressure, means to normally limit the movement of the valve in closing when the generator is in an upright position whereby the reduced part of the valve will normally close the feed-opening, and means independent of the gas-pressure to force the lower large part of the valve up to close the feed-opening when the generator is moved from its upright position.

27. An acetylene-gas generator comprising, a carbid-holder, a water-holder, a feed mechanism normally opening the feed-valve against gas-pressure, a freely-movable device to limit the movement of the valve in closing under normal conditions and shifting to permit the valve to have an additional movement in closing when the generator is moved a predetermined distance from a vertical position, means whereby this additional movement of the valve will convert the valve-opening means into a valve-closing means, and means for returning the valve-opening means to its normal operative position.

28. An acetylene-gas generator comprising, a water-holder, a carbid-holder, a flexible gas-tight wall across the carbid-holder, a perforated plate in the carbid-holder below the flexible wall and forming a protected space or chamber for the flexible wall, a filter covering said perforated plate, and a feed-valve connected to said flexible wall.

29. An acetylene-gas generator comprising, a lower water-holder, an upper carbid-holder, a flexible gas-tight wall across the top of the carbid-holder, a downward and inward inclined perforated filter-support below the flexible wall and extending across the carbid-holder to form a protected compartment for the flexible wall, a filter secured to said support, a central depending guide-tube secured to the center of said filter-support, a valve-rod secured to the flexible wall and extending through the guide-tube, a feed-valve on said rod, and means for forming a gas-tight joint between said valve and the guide-tube.

30. An acetylene-gas generator comprising, a lower water-holder, an upper carbid-holder, a flexible gas-tight wall across the top of the carbid-holder, a downward and inward inclined support below the flexible wall and extending across the carbid-holder to form a protected compartment for the flexible wall, a filter through which gas passes to the diaphragm, a central depending guide-tube secured to the center of said support, a valve-rod secured to

the flexible wall and extending through the guide-tube, a feed-valve detachably connected to the lower end of said rod whereby the compartment formed by the support may be readily cleaned through the lower end of the guide-tube.

31. An acetylene-gas generator comprising a water-holder, a carbide-holder, a feed-valve, a horizontal movable wall subject to the pressure of the gas generated, means for connecting said movable wall to the feed-valve to close said valve by gas-pressure, a lever operatively connected to said movable wall, a spring device connected to said lever and tending to depress the movable wall, a freely-movable body for limiting the movement of the movable wall when the generator is in an upright position and adapted to shift to permit the movable wall to have an additional upward movement when the generator is out of its vertical position, means whereby this additional travel of the movable wall will transform the valve-opening means into a valve-closing means, and means interposed between a 5 the movable wall and the spring whereby a

downward pull on the valve-rod will return the valve-opening means to its normal operative position.

32. An acetylene-gas generator comprising a carbide-holder, a water-holder, a feed-valve, 30 a spring normally tending to open said valve, and means operated by gas-pressure when the generator is moved a predetermined distance from a vertical position to reverse the operation of the tension of the spring and thereby 35 convert it into a valve-closing spring to maintain the valve closed, means to return the valve-opening means to its normal operating position and means to prevent a sudden and violent movement of the valve when the valve-opening means is returned to its normal operating position.

In testimony whereof I hereunto affix my signature, in the presence of two witnesses, this 15th day of June, 1904.

CHARLES W. BECK.
